UNITED STATES PATENT OFFICE.

VERNE P. ALEXANDER, OF CHICAGO, ILLINOIS, ASSIGNOR OF ONE-HALF TO NICHOLAS KOENIG, OF CHICAGO, ILLINOIS.

BANK NOVELTY.

Application filed November 3, 1923. Serial No. 672,692.

To all whom it may concern:

Be it known that I, VERNE P. ALEXANDER, a citizen of the United States, residing at Chicago, in the county of Cook and State 5 of Illinois, have invented certain new and useful Improvements in Bank Novelties, of which the following is a specification.

My invention relates generally to portable savings banks and more particularly to the 10 provision of a novel and improved separably connected super-structure therefor in the nature of a display frame or similar device.

As its primary object the invention 15 contemplates the provision of a novel and improved separable connection for use as above indicated but which will be capable of general utility for connecting frame and base members or analogous structures.

Another object of the invention is to provide a bank in the form of a picture frame and stand having a coin receiving supporting base to which the frame is separably connected.

A further object of the invention is to furnish a device of this character embodying few parts, which will be neat and attractive in appearance, strong and durable in construction and relatively inexpensive 30 of manufacture.

The above and other objects are attained by a novel combination and arrangement of parts to be hereinafter described and claimed and in order that the same may 35 be better understood, reference is had to the accompanying drawing forming a part of this specification.

In the drawing,

Figure 1 is a front elevation of a bank 40 constructed in accordance with my invention;

Fig. 2 is an end elevation thereof;

Fig. 3 is a section on the line 3—3 of Fig. 2;

Fig. 4 is a section on the line 4—4 of Fig. 3, and

Fig. 5 is a group perspective showing various parts in disassembled relation.

Referring specifically to the drawing 50 wherein like reference characters designate like parts throughout all views, numeral 5 denotes the hollow base or coin receptacle having a hinged door 6 in its bottom whereby the coins inserted through a slot 7 may be removed after operating the lock 8.

The base 5 will preferably be formed of metal although wood or other material may be used if desired. The top of the base 5 carries a pair of spaced studs 9 having rounded heads 9^a tapering to reduced necks 9^b. It might be stated in passing that the studs 9 are substantially identical with the conventional stud of the snap fasteners used in the clothing art they being here employed for an analogous purpose, as will be present- 60 ly apparent.

The picture frame 10 is pivoted at 11 to the arms 12 of a U-shaped support, the horizontal portion 13 of which is provided in its side remote from the frame 10 with 70 a longitudinal recess 14 of sufficient depth to receive the studs 9 when the support rests upon the base 5. A plate 15 secured by means of screws 16 serves to close the recess 14 and it carries upon its inner surface a 75 pair of spaced and parallel spring members 17 both of which are fastened to the plate intermediate their ends by soldering as indicated at 18. Other modes of fastening the spring members 17 may, however, be re- 80 sorted to if described.

The spring members 17 are spaced a distance less than the width of the stud heads 9^a while the plate 15 is provide with suitable transverse apertures 19 for the reception of the same. 85

Therefore, upon insertion of the studs 9 into the apertures 19 the heads 9^a will cause the spring members 17 to separate momentarily and upon complete insertion of the 90 studs they will grip the stud necks 9^b for separably connecting the support 13 with its frame 10 to the base 5.

Obviously the members may be readily separated and attached as desired and while 95 I have described and illustrated herein the preferred embodiment of my invention in accordance with the patent statutes, yet it will be distinctly understood that I do not propose to limit myself strictly thereto since 100 various changes and modifications thereof will immediately suggest themselves to those skilled in the art without departing from the spirit of the invention, the scope of which is defined by the following claims. 105

What I claim as new and desire to secure by Letters Patent is:

1. The combination with a picture frame; of a hollow base, studs projecting from the top of said base, the bottom rail of said 110

picture frame having a recess for receiving said studs, and yieldable stud retaining means carried within said stud receiving recess and disposed in the path of said 5 studs.

2. The combination with a picture frame; of a hollow base, studs projecting from the top of said base, the bottom rail of said picture frame having stud receiving portions, a base plate for said bottom rail and attachable thereto, said base plate having openings therein for establishing communication with said stud-receiving portions, and yieldable stud-gripping members carried by 10 said base plate and disposed inwardly of the same in the path of said studs.

3. The combination with a picture frame; of a hollow base, studs projecting from the top of said base, the bottom rail of said picture frame having stud-receiving portions, a base plate for said bottom rail and attachable thereto, said base plate having openings therein for establishing communication with said stud-receiving portions, and yieldable stud-gripping members carried by 20 said base plate and disposed inwardly of the same in the path of said studs, said members being parallel spring rods disposed in spaced relation in the path of said studs.

In testimony whereof I affix my signature.

VERNE P. ALEXANDER.
